VENTED TOILET

Charles C. Rosselle, Detroit, Mich.

Application February 1, 1949, Serial No. 73,950

10 Claims. (Cl. 4—215)

1

This invention relates to vented toilets, and in particular to jet type vented toilets.

The primary object of the invention is to provide a jet type vented toilet wherein a primary jet is employed to vent the toilet when the toilet seat is Down and in use coupled with a secondary jet which opens a normally closed vent closure valve disposed in the toilet, which vent closure valve closes automatically responsive to flushing the toilet when the toilet seat is Down and in use when the toilet is flushed, all permitting the use of standard toilet bowls and standard plumbing connections to and from the toilet bowl.

A further object of the invention is to provide a jet type vented toilet wherein primary and secondary jets operable responsive to a person sitting on the toilet seat and a normally closed vent closure valve are employed, the primary jet creating a negative pressure in the wash down ring of the toilet bowl whereby to withdraw vitiated air from the bowl to a vented sewer system, the secondary jet simultaneously opening the normally closed vent closure valve, all arranged to permit the flushing of the bowl to overcome the effect of the secondary jet and permit the vent closure valve to close during the flushing of the toilet bowl.

Other objects of the invention will become apparent by reference to the following detailed description taken in connection with the accompanying drawings, in which:

Fig. 1 is a vertical sectional view of a jet type vented toilet embodying the invention.

Fig. 2 is a top plan view of the construction disclosed in Fig. 1.

Fig. 3 is a fragmentary rear elevational view of the construction disclosed in Figs. 1 and 2.

Fig. 4 is an enlarged fragmentary longitudinal sectional view through the toilet bowl and jet vent and jet vent control mechanism embodying the invention, the jet vent unit being shown in its operating position with the vent closure valve Open.

Fig. 5 is an enlarged fragmentary view similar to Fig. 4 showing the jet vent unit in its normal inoperative position with the vent closure valve Closed.

Fig. 6 is a top plan view of the vent closure valve in its normal Closed position.

Fig. 7 is a side elevational view of the vent closure valve shown in Fig. 6 in its Open position taken on the line 7—7 of Fig. 4.

Fig. 8 is a vertical sectional view of a spring loaded plunger employed to lift the toilet seat when not in use, the toilet seat and plunger being shown in their In Use position.

2

Fig. 9 is a horizontal sectional view taken on the line 9—9 of Fig. 8.

Fig. 10 is a fragmentary top plan view taken on the line 10—10 of Fig. 4 showing the connection preferably employed between the seat hinge and the jet vent unit employed.

Referring now to the drawings wherein like numerals refer to like and corresponding parts throughout the several views, the particular embodiment of the invention disclosed for the purpose of illustration is shown in connection with a standard tank type toilet bowl 20 connected to a drain 21 having the usual vent 22, a pressure water supply line 23 running to the toilet tank 24, and a hinged toilet seat 25, and comprises in general, a jet vent unit 26 having a pressure water line 230 running thereto from the pressure water supply line 23 and including a shut-off valve 27, a primary jet 28 and a secondary jet 29 disposed in the flush passage 201 of the toilet bowl 20 located between the tank 24 and the wash down ring 202 of the said toilet bowl 20, a counter-weighted normally closed butterfly type vent closure valve 30 disposed between the flush passage 201 and the drain chamber 203 of the toilet bowl 20, which drain chamber 203 is separated from the receiving chamber 204 of the toilet bowl 20 by the usual water seal baffle 205 thereof, the said vent closure valve 30 being provided with a jet target flap 31 by means of which the said vent closure valve 30 is opened responsive to water from the secondary jet jetted thereagainst and closed responsive to water passing through the flush passage 201 to and through the wash down ring 202 of the toilet bowl 20, a linkage 32 between the hinged toilet seat 25 and the shut-off valve 27 of the jet vent unit 26 maintaining the said shut-off valve 27 closed except when the toilet seat 25 is fully down, and a spring loaded plunger 33 mounted on the toilet seat 25 preventing the said toilet seat 25 from assuming its fully down position unless the said toilet seat is occupied.

The toilet bowl 20 is of standard construction and, as best illustrated in Fig. 4, the said toilet bowl 20 is provided with apertures 206, 207 and 208 to accommodate the jet vent unit 26, the water supply line 230 and the vent closure valve 30 respectively.

The jet vent unit 26 comprises a housing 34 preferably threaded into an interiorly threaded sleeve 35 cemented or otherwise secured in the aperture 206 provided in the bowl 20 above the flush passage 201 and drain chamber 203 thereof. The said housing 34 of the jet vent unit 26 is bored and counterbored axially to provide a

tapered valve seat 36 and to accommodate a reciprocating valve member 27 having a tapered lower end 270 which seats on the said valve seat 36. The said housing 34 of the jet vent unit 26 is provided with a threaded inlet aperture 340 at the side thereof to accommodate the water supply line 230, and is provided with a primary jet aperture 28 at the bottom thereof directed concentrically into the vent closure valve 30 therebelow and a secondary jet aperture 29 diagonally through the side thereof directed toward the jet target flap 31 of the said vent closure valve 30, both the primary jet aperture 28 and the secondary jet aperture 29 being located in such a position that the reciprocating valve member 27 prevents the passage of water from the water supply line 230 therethrough when the tapered lower end 270 of the reciprocating valve member 27 is seated on the valve seat 36. The reciprocating valve member 27 extends upwardly from the top of the housing 34 of the jet vent unit 26 through suitable guide nut 33, packing 39 and a gland nut 40. The said reciprocating valve member 27 is spring loaded by a compression spring 41 engaging the reciprocating valve member at a shoulder 2700 provided just above the lower tapered end 270 thereof and reacting against the bottom of the guide nut 38.

When the hinged toilet seat 25 is occupied and in its full down position as shown in Fig. 4, the spring loaded reciprocating valve member 27 is engaged and lifted by an arm 42 rotatably mounted on the hinge rod 43 of the toilet seat 25 engaged by a pin 44 disposed through the said hinge rod 43 and through a slot 420 in the said arm 42, the said arm 42 being bifurcated at its outer end 4200 and positioned over a shouldered ferrule 45 threaded on the upper extending end of the said reciprocating valve member 27. The said ferrule 45 is fixed in its proper adjusted position by upper and lower lock nuts 46 and 47, the upper lock nut 46 serving as an abutment against which the bifurcated end 421 of the arm 42 reacts when lifting the valve member 27.

A suitable spring loaded plunger 33 mounted by screws 48 in the bottom of the forward end of the toilet seat 25 lifts the hinged toilet seat 25 about the hinge rod 43 when unoccupied to such an angle as will release the valve member 27 of the jet vent unit 26 and shut off the primary jet 28 and the secondary jet 29 when the toilet is not in use, see Fig. 5. The toilet seat hinges 49 are of the usual construction, except that the toilet seat hinges 49 are rigidly pinned by pins 490 to the hinge rod 43, and the hinge rod 43 is rotatably mounted in the hinge rod support brackets 50. The toilet seat lid (not shown) is hinged to the hinge rod 43 by suitable hinge members 51 rotatably mounted thereon.

The particular style of spring loaded plunger 33 shown in the drawings comprises an annular inwardly and outwardly flanged housing 52 secured by screws 48 to the bottom of the front of the toilet seat 25 over a circular recess 53 formed in the said toilet seat 25. An inwardly and outwardly flanged annular reciprocating member 54 having an outwardly flanged plunger 33 reciprocatingly mounted therein is positioned in the inwardly and outwardly flanged annular housing 52, as best illustrated in Fig. 8, with a compression spring 55 positioned within the plunger 33 reacting against the toilet seat at the bottom of the circular recess 53 therein. When the toilet seat 25 is occupied, the spring loaded plunger 33 assumes the position shown

in Figs. 4 and 8. When the toilet seat 25 is unoccupied, the spring loaded plunger 33 lifts the front end of the toilet seat 25 and causes it to assume a partially elevated position as indicated in Figs. 1 and 5.

The vent closure valve 30 comprises a tubular housing 56 having an external flange 560 therearound to position the said tubular housing in the aperture 208 formed in the horizontal floor 10 209 at the front of the flush passage 201 above the drain chamber 203 of the toilet bowl 20, the said aperture 208 being in alignment with and concentrically under the jet vent unit 26 whereby to cause the housing 56 of the vent closure valve 15 30 to serve as a jet eduction tube for the primary jet 28. When the shut-off valve 27 of the jet vent unit 26 is open, a spray of water from the primary jet 28 passes through the tubular housing 56 of the vent closure valve 30 which 20 creates a negative pressure within the flush passage 201 of the toilet bowl 20, and, since the said flush passage 201 is connected by the aperture 209 to the flush down ring 202 which has flush holes 2020 therein, vitiated air is drawn 25 from the receiving chamber 204 of the toilet bowl 20 when the toilet seat 25 is occupied due to the fact that occupancy of the toilet seat 25 opens the jet shut-off valve 27 of the vent unit 26 whereupon water under pressure sprays forcibly 30 from both the primary jet 28 and the secondary jet 29 of the said vent unit 26.

The said vent closure valve 30 is provided with a butterfly valve member 57 therein mounted on a turnable crank arm 58 journaled through the 35 tubular housing 56. The said vent closure valve 30 is also provided with a jet target flap 31 mounted on the outside thereof on a turnable crank arm 59 journaled across one side of the tubular housing 56 parallel to the said crank 40 arm 58. The outer ends of the crank arms 58 and 59 are linked together by means of a counterweight 60 journaled thereon, which counterweight 60 normally holds the butterfly valve member 57 of the vent closure valve 30 closed by 45 gravity action. However, when the toilet seat 25 is occupied, the shut-off valve 27 of the jet vent unit 26 is opened and water under pressure from the pressure water lines 23 and 230 passes 50 through the jet vent unit 26 and out of the primary jet 28 and out of the secondary jet 29. The secondary jet 29 strikes the jet target flap 31 of the vent closure valve 30 and opens the butterfly valve member 57 which permits the primary jet 28 to discharge continuously through the tubular 55 housing 56 of the said vent closure valve 30 serving as a jet eduction tube for withdrawing vitiated air from the receiving chamber 204 of the toilet bowl 20 as hereinbefore described.

If the toilet is flushed when occupied, the rush 60 of flushing water from the toilet tank 24 strikes the jet target flap 31, overcomes the pressure of the secondary jet 29 thereon, and closes the vent closure valve 30 during the flushing of the toilet, otherwise, the flushing water would pass down 65 the vent closure valve 30, through the drain chamber 203 and into the drain 21 through the vent 22.

Thus, a jet type vented toilet embodying the 70 invention is fully automatic and operates responsive to the occupation of the toilet seat. It employs standard plumbing and standard toilet bowl construction. It employs a combination dual jet vent unit wherein the primary jet functions to remove vitiated air from the occupied

toilet and the secondary jet opens a normally closed vent closure valve to permit the primary jet to function, and, if the toilet is flushed when occupied, the flushing water employed overcomes the effect of the secondary jet and closes the vent closure valve.

Although but one specific embodiment of the invention has been disclosed and described in detail, it is obvious that many changes may be made in the size, shape, arrangement and detail of the various elements of the invention without departing from the spirit and scope thereof as defined by the appended claims.

I claim:

1. A jet vent mechanism for toilets comprising, in combination, a jet vent unit and a vent closure valve disposed in spaced alignment with respect to the said jet vent unit, the said jet vent unit including a housing, a pressure water supply connected thereto, primary and secondary water jets and a valve normally shutting off the water supply from the said primary and secondary jets, and the vent closure valve including a tubular housing serving as a jet eduction tube, a pivoted gravity closed vent closure valve member disposed in the said jet eduction tube normally closing the same, a secondary jet target flap coupled with the said vent closure valve, the primary jet of the jet vent unit being directed through the said eduction tube causing a passage of air therethrough and the secondary jet being directed against the said secondary jet target flap of the vent closure valve whereby to open the said vent closure valve, and means for opening the said water supply valve to the said primary and secondary jets.

2. A jet vent mechanism for toilets comprising, in combination, a jet vent unit and a vent closure valve disposed in spaced alignment with respect to the said jet vent unit, the said jet vent unit including a housing, a pressure water supply connected thereto, primary and secondary water jets and a valve normally shutting off the water supply from the said primary and secondary jets, and the vent closure valve including a tubular housing serving as a jet eduction tube, a pivoted vent closure valve member disposed in the said jet eduction tube, a counterweighted linkage connecting the said secondary jet target flap and the pivoted vent closure valve member normally maintaining the vent closure valve closed, the primary jet of the jet vent unit being directed through the said eduction tube causing a passage of air therethrough and the secondary jet being directed against the said secondary jet target flap of the vent closure valve whereby to open the said vent closure valve, and means for opening the said water supply valve to the said primary and secondary jets.

3. In a toilet of the type having a toilet bowl including a receiving chamber and a drain chamber connected to a drain and the drain connected to a vent and wherein the toilet includes a flush passage connected to an apertured wash down ring disposed around the receiving chamber, jet vent mechanism comprising, in combination, a jet vent unit disposed in the flush passage and a vent closure valve disposed in spaced alignment with respect to the said jet vent unit and connecting the flush passage and the drain chamber, the said jet vent unit including a housing, a pressure water supply connected thereto, primary and secondary water jets and a valve normally shutting off the water supply from the said primary and secondary jets, and the vent closure

valve including a tubular housing serving as a jet eduction tube, a pivoted gravity closed vent closure valve member disposed in the said jet eduction tube normally closing the same, a secondary jet target flap coupled with the said vent closure valve, the primary jet of the jet vent unit being directed through the said eduction tube causing a passage of air therethrough and the secondary jet being directed against the said secondary jet target flap of the vent closure valve whereby to open the said vent closure valve, and means for opening the said water supply valve to the said primary and secondary jets.

4. In a toilet of the type having a toilet bowl including a receiving chamber and a drain chamber connected to a drain and the drain connected to a vent and wherein the toilet includes a flush tank and a flush passage connected from the flush tank to an apertured wash down ring disposed around the receiving chamber, jet vent mechanism comprising, in combination, a jet vent unit disposed in the flush passage and a vent closure valve disposed in spaced alignment with respect to the said jet vent unit and connecting the flush passage and the drain chamber, the said jet vent unit including a housing, a pressure water supply connected thereto, primary and secondary water jets and a valve normally shutting off the water supply from the said primary and secondary jets, and the vent closure valve including a tubular housing serving as a jet eduction tube, a pivoted gravity closed vent closure valve member disposed in the said jet eduction tube normally closing the same, a secondary jet target flap coupled with the said vent closure valve, the primary jet of the jet vent unit being directed through the said eduction tube causing a passage of air therethrough and the secondary jet being directed against the said secondary jet target flap of the vent closure valve whereby to open the said vent closure valve, the said secondary jet target flap being located to permit flush water from the flush tank passing through the flush passage to the wash down ring to close the said vent closure valve during the flushing of the toilet, and means for opening the said water supply valve to the said primary and secondary jets.

5. In a toilet of the type having a toilet bowl and a hinged toilet seat thereover, the said toilet including a receiving chamber and a drain chamber connected to a drain and the drain connected to a vent and wherein the toilet includes a flush tank and a flush passage connected from the flush tank to an apertured wash down ring disposed around the receiving chamber, jet vent mechanism comprising, in combination, a jet vent unit disposed in the flush passage and a vent closure valve disposed in spaced alignment with respect to the said jet vent unit and connecting the flush passage and the drain chamber, the said jet vent including a housing, a pressure water supply connected thereto, primary and secondary water jets and a valve normally shutting off the water supply from the said primary and secondary jets, and the vent closure valve including a tubular housing serving as a jet eduction tube, a pivoted gravity closed vent closure valve member disposed in the said eduction tube normally closing the same, a secondary jet target flap coupled with the said vent closure valve, the primary jet of the jet vent unit being directed through the said eduction tube causing a passage of air therethrough and the secondary jet being directed against the said secondary jet target flap of the vent closure valve whereby to open the said vent

closure valve, the said secondary jet target flap being located to permit flush water from the flush tank passing through the flush passage to the wash down ring to close the said vent closure valve during the flushing of the toilet, spring loaded means preventing the toilet seat from assuming a horizontal position except when occupied, and a linkage between the hinged toilet seat and the said water supply valve for opening the said water supply valve to the said primary and secondary jets responsive to occupation of the toilet seat.

6. A jet vent mechanism for tank type flush toilets employing a hinged toilet seat comprising, in combination, a jet vent unit and a vent closure valve disposed in spaced alignment with respect to the said jet vent unit, the said jet vent unit including a housing, a pressure water supply connected thereto, primary and secondary water jets and a valve normally shutting off the water supply from the said primary and secondary jets, and the vent closure valve including a tubular housing serving as a jet eduction tube, a pivoted gravity closed vent closure valve member disposed in the said jet eduction tube normally closing the same, a secondary jet target flap located in the path of flush water through the toilet coupled with the said vent closure valve, the primary jet of the jet vent unit being directed through the said eduction tube causing a passage of air therethrough and the secondary jet being directed against the said secondary jet target flap of the vent closure valve whereby to open the said vent closure valve, and means operable responsive to occupying the toilet seat for opening the said water supply valve to the said primary and secondary jets, the flushing of the toilet when occupied causing flush water passing through the toilet acting on the secondary jet target flap of the vent closure valve to overcome the secondary jet and close the said vent closure valve during flushing of the toilet when occupied.

7. In a toilet of the type having a toilet bowl including a receiving chamber and a drain chamber connected to a drain and the drain connected to a vent and wherein the toilet includes a flush passage connected to an apertured wash down ring disposed around the receiving chamber, jet vent mechanism comprising, in combination, a jet vent unit disposed in the flush passage and a vent closure valve disposed in spaced alignment with respect to the said jet vent unit and connecting the flush passage and the drain chamber, the said jet vent unit including a housing, a pressure water supply connected thereto, primary and secondary water jets and a valve normally shutting off the water supply from the said primary and secondary jets, and the vent closure valve including a tubular housing serving as a jet eduction tube, a pivoted gravity closed vent closure valve member disposed in the said jet eduction tube normally closing the same, a secondary jet target flap pivotally mounted outside the said jet eduction tube, a counterweighted linkage connecting the said secondary jet target flap and the pivoted vent closure valve member normally maintaining the vent closure valve closed, the primary jet of the jet vent unit being directed through the said eduction tube causing a passage of air therethrough and the secondary jet being directed against the said secondary jet target flap of the vent closure valve whereby to open the said vent closure valve, and means for opening the said water supply valve to the said primary and secondary jets.

8. In a toilet of the type having a toilet bowl including a receiving chamber and a drain chamber connected to a drain and the drain connected to a vent and wherein the toilet includes a flush tank and a flush passage connected from the flush tank to an apertured wash down ring disposed around the receiving chamber, jet vent mechanism comprising, in combination, a jet vent unit disposed in the flush passage and a vent closure valve disposed in spaced alignment with respect to the said jet vent unit and connecting the flush passage and the drain chamber, the said jet vent unit including a housing, a pressure water supply connected thereto, primary and secondary water jets and a valve normally shutting off the water supply from the said primary and secondary jets, and the vent closure valve including a tubular housing serving as a jet eduction tube, a pivoted gravity closed vent closure valve member disposed in the said jet eduction tube normally closing the same, a secondary jet target flap pivotally mounted outside the said jet eduction tube, a counterweighted linkage connecting the said secondary jet target flap and the pivoted vent closure valve member normally maintaining the vent closure valve closed, the primary jet of the jet vent unit being directed through the said eduction tube causing a passage of air therethrough and the secondary jet being directed against the said secondary jet target flap of the vent closure valve whereby to open the said vent closure valve, the said secondary jet target flap being located to permit flush water from the flush tank passing through the flush passage to the wash down ring to close the said vent closure valve during the flushing of the toilet, and means for opening the said water supply valve to the said primary and secondary jets.

9. In a toilet of the type having a toilet bowl and a hinged toilet seat thereover, the said toilet including a receiving chamber and a drain chamber connected to a drain and the drain connected to a vent and wherein the toilet includes a flush tank and a flush passage connected from the flush tank to an apertured wash down ring disposed around the receiving chamber, jet vent mechanism comprising, in combination, a jet vent unit disposed in the flush passage and a vent closure valve disposed in spaced alignment with respect to the said jet vent unit and connecting the flush passage and the drain chamber, the said jet vent unit including a housing, a pressure water supply connected thereto, primary and secondary water jets and a valve normally shutting off the water supply from the said primary and secondary jets, and the vent closure valve including a tubular housing serving as a jet eduction tube, a pivoted gravity closed vent closure valve member disposed in the said eduction tube normally closing the same, a secondary jet target flap pivotally mounted outside the said jet eduction tube, a counterweighted linkage connecting the said secondary jet target flap and the pivoted vent closure valve member normally maintaining the vent closure valve closed, the primary jet of the jet vent unit being directed through the said eduction tube causing a passage of air therethrough and the secondary jet being directed against the said secondary jet target flap of the vent closure valve whereby to open the said vent closure valve, the said secondary jet target flap being located to permit flush water from the flush tank passing through the flush passage to the wash down ring to close the said vent closure valve during the flushing of the toilet, and means for opening the said water supply valve to the said primary and secondary jets.

toilet, spring loaded means preventing the toilet seat from assuming a horizontal position except when occupied, and a linkage between the hinged toilet seat and the said water supply valve for opening the said water supply valve to the said primary and secondary jets responsive to occupation of the toilet seat.

10. A jet vent mechanism for tank type flush toilets employing a hinged toilet seat comprising, in combination, a jet vent unit and a vent closure valve disposed in spaced alignment with respect to the said jet vent unit, the said jet vent unit including a housing, a pressure water supply connected thereto, primary and secondary water jets and a valve normally shutting off the water supply from the said primary and secondary jets, and the vent closure valve including a tubular housing serving as a jet eduction tube, a pivoted gravity closed vent closure valve member disposed in the said jet eduction tube normally closing the same, a secondary jet target flap located in the path of flush water through the toilet pivotally mounted outside the said jet eduction tube, a counterweighted linkage connecting the said secondary jet target flap and the pivoted vent closure valve member normally

5 maintaining the vent closure valve closed, the primary jet of the jet vent unit being directed through the said eduction tube causing a passage of air therethrough and the secondary jet being directed against the said secondary jet target flap of the vent closure valve whereby to open the said vent closure valve, and means operable responsive to occupying the toilet seat for opening the said water supply valve to the said primary and secondary jets, the flushing of the toilet when occupied causing flush water passing through the toilet acting on the secondary jet target flap of the vent closure valve to overcome the secondary jet and close the said vent closure valve during flushing of the toilet when occupied.
